UNITED STATES PATENT OFFICE.

WILLIAM F. CUNNINGHAM, OF BROOKLYN, NEW YORK.

SECTIONAL STEAM-BOILER.

SPECIFICATION forming part of Letters Patent No. 593,836, dated November 16, 1897.

Application filed July 16, 1897. Serial No. 644,776. (No model.)

To all whom it may concern:

Be it known that I, WILLIAM F. CUNNINGHAM, of the city of Brooklyn, in the county of Kings and State of New York, have invented 5 a new and useful Improvement in Sectional Steam-Boilers, of which the following is a specification.

This invention, which is applicable to sectional boilers the sections of which may be of 10 various forms, relates particularly to the setting or casing within which the sections are inclosed and to the arrangement of the sections and flue-spaces within said casing or setting, as hereinafter described and claimed, 15 whereby nearly all parts of the several sections are exposed to the circulating gaseous products of combustion and a very extensive heating-surface is obtained.

Figure 1 of the accompanying drawings represents 20 a transverse vertical section of a sectional boiler and its setting or casing embodying my invention; Fig. 2, a central longitudinal section of the same; Fig. 3, a horizontal section about on the line 3 3 of Fig. 1.

Similar letters of reference designate corresponding parts in all the figures.

A A designate the several sections of the boiler. B designates the setting or casing which surrounds and incloses the several sections 30 and which may be of brickwork or iron, but is represented as having its sides and back of brickwork, its front of iron, and its crown or roof of iron covered in with brick-work. The several sections A A are represented as in two series, arranged one series on each side of the center of the fire-grate C and so formed as to include within their lower parts a central fire-chamber D. The several sections are each connected at its upper end 40 by a short pipe a with a steam-drum E, and they are connected each at its lower end by a pipe b passing through the setting with one of two water-supply drums F F arranged outside of the setting, the said drums being supplied with water through pipes c c. The particular form of the sections and their connections are, however, immaterial to my invention, all that is essential in the sections being 45 that a fire-chamber is formed within or between them and that they are set at such a distance apart, as shown in Figs. 2 and 3, as

to form between them narrow flues d d, which diverge laterally from the fire-chamber.

The sides of the setting or casing B are so spaced outwardly or laterally from the sections A A, as shown in Figs. 1 and 3, as to form flues e e, running along the whole series of sections on each side of the boiler, the said spaces or flues being closed in the front and having no outlet but at the rear of the boiler, 55 where the setting is carried so far back as to form an upright flue f, (see Figs. 2 and 3,) represented as of the whole width of the boiler. From this flue the outlet is at its rear to the rear end of a flue g, which is also 60 represented as of the full width of the boiler and which runs over the tops of the sections A between them and the roof or crown of the setting or casing, the outlet h from said flue 65 g to the uptake or chimney being near the front end of the boiler.

The back flue f is formed between the rear-most sections A and the rear wall of the setting or casing partly by a wall i built across the rear of the fire-chamber and partly by a 75 plate j, arranged above and forming an upward continuation of said wall close in rear of the sections A, the said wall and plate being no wider than the sections and having on each side of them communication with the side 80 flues. The spaces between the tops of the sections A A and the steam-drum E are closed by plates k k, and the spaces between the upper parts of the several sections are fitted at the top by suitable means, as plates p, Fig. 1, 85 to prevent any directly-upward communication between the lateral flues d and the top flue g. Direct upward communication from the side flues e to the top flue g is prevented by the side walls of the casing being formed 90 with inward projections l along so much of their interiors as includes the whole series of sections A, the said projections fitting closely to the several sections on each side of the boiler.

95

The circulation of the gaseous products of combustion from the fire-chamber to the flue-outlet or smoke-pipe h is first from the fire-chamber, laterally through the narrow flues d d between the boiler-sections, as indicated 100 by the arrows 4 4 in Figs. 1 and 3, to the side flues e e, then along the said side flues, as in-

dicated by the arrows 5 5, to the back flue *f*, up which they pass, as indicated by the arrows 6 6, to the top flue *g*, and through the latter over the upper parts of the sections, as indicated by the arrows 7 7, to the chimney. This circulation includes almost every portion of the surface of every section.

A clean-out door *G* is represented at the bottom of the back flue *f* and one, *H*, above the sections *A A*.

This improvement applies not only to boilers for generating steam, but to so-called boilers which are simply water-heaters.

What I claim as my invention is—

1. In a sectional boiler and a setting or casing therefor, the combination of a series of boiler-sections including within them a central fire-chamber and having between them spaces forming flues which diverge laterally from said chamber but are closed at the top, and side flues with which said laterally-divergent flues severally communicate and from which there are outlets common to the said laterally-divergent flues, substantially as herein set forth.

2. In a sectional boiler and a setting or casing therefor, the combination of a series of boiler-sections including within them a central fire-chamber and having between them

spaces forming flues which diverge laterally 30 from said chamber but are closed at the top, side flues with which the said laterally-divergent flues severally communicate, a back flue with which said side flues communicate in rear of the several sections, and a top flue 35 with which said back flue communicates and which runs over the several sections, substantially as herein described.

3. The combination of the boiler-sections *A A* arranged in two opposite series those of 40 each series being separated by flue-spaces *d d*, the central fire-chamber *D* between the two series of sections, the plates *p p* closing the flue-spaces *d d* at the top of said sections, the wall *i j* in rear of said sections, and the inclosing casing *B* within which are formed the flues *e e f* and *g*, the said flues *e e* forming lateral outlets to the flue-spaces *d d*, the flue *f* forming an outlet in rear of the sections *A A* and wall *i j* from the rear of the flues *e e*, 50 and the flue *g* forming an outlet above the sections *A A* and wall *i j* from the said flue *f* to the chimney-outlet *h*, all substantially as herein described.

WILLIAM F. CUNNINGHAM.
